UNITED STATES PATENT OFFICE

158,248

NUTCRACKER

Andrew C. Brookey, San Antonio, Tex.

Application June 1, 1948, Serial No. 146,699

Term of patent 3½ years

(Cl. D44—1)

To all whom it may concern:

Be it known that I, Andrew C. Brookey, a citizen of the United States, residing in the city of San Antonio, county of Bexar, State of Texas, have invented a new, original, and ornamental Design for Nutcrackers, of which the following is a specification, reference being had to the accompanying drawing, forming part thereof, and in which

Figure 1 is a side elevation;

Figure 2 is an end elevation; and

Figure 3 is a view similar to Figure 1 but showing the reverse side of the nutcracker.

I claim:

The ornamental design for a nutcracker, as shown.

ANDREW C. BROOKEY.
